UNITED STATES PATENT OFFICE.

CHARLES IRWIN LATTIG, OF GLENSIDE, PENNSYLVANIA, ASSIGNOR TO LATTIG,
SHIMER MFG. CO., OF BETHLEHEM, PENNSYLVANIA.

COMBINATION DESK-CHAIR.

1,195,240.

Specification of Letters Patent. Patented Aug. 22, 1916.

Application filed April 5, 1915. Serial No. 19,335.

To all whom it may concern:

Be it known that I, CHARLES IRWIN LATTIG, a citizen of the United States, residing at Glenside, in the county of Montgomery 5 and State of Pennsylvania, have invented certain new and useful Improvements in Combination Desk-Chairs, of which the following is a specification.

My invention relates to improvements in 10 combination desk chairs, the object of the invention being to provide a strong and rigid chair with improved desk supporting means, whereby the desk may be adjusted vertically or positioned at any desired angle, and also 15 move toward and away from the occupant of the chair to enable the desk to be positioned exactly as desired.

A further object is to provide a chair in 20 which the vertical and horizontal supports are of metal pipe connected by angles and T-couplings, and rigidly supporting the chair seat and the desk, the latter capable of adjustment vertically and angularly as well as horizontally to suit the occupant of the 25 chair.

A further object is to provide a chair of 30 the character stated which will be neat and attractive in appearance, comparatively cheap to manufacture, and strong and durable in use.

With these and other objects in view, the invention consists in certain novel features of construction and combinations and arrangements of parts as will be more fully 35 hereinafter described and pointed out in the claims.

In the accompanying drawings: Figure 1 is a view in side elevation illustrating my improved combination desk chair. Fig. 2 is 40 a view in front elevation of Fig. 1. Fig. 3 is a top plan view. Fig. 4 is a view partly in elevation and partly in section, the section being taken on the line 4—4 of Fig. 2. Fig. 5 is a top plan view with the desk removed, 45 the position of the desk being indicated by the dotted line. Fig. 6 is a fragmentary view in transverse section on the line 6—6 of Fig. 1. Fig. 7 is a view in section on an enlarged scale illustrating the clamp 22, the 50 section being taken on the line 7—7 of Fig. 1. Fig. 8 is a fragmentary view on an enlarged scale in section on the line 8—8 of Fig. 2.

1 represents a chair seat which is 55 supported on horizontal rods 2, the latter se-

cured to vertical rods 3 and 4. The rods 3 are at the rear of the seat and extend above the seat, and are connected by cross bar 5, which is connected by a board 6 with seat 1, and constitutes the back of the chair. 60

The two rear rods 3 constitute chair legs, while the rod 4 at the left of the chair constitutes one of the front legs. The other rod corresponding to rod 4 and which for clearness of description I have given the reference numeral 8, is located parallel with a projected leg 7. This leg 7 also consists of a rod extending to the floor. Horizontal rods 9 located an appreciable distance below rod 2, connect the several vertical rods 3, 4, 8, 70 and 7, and a horizontal rod 10 at the right hand side of the chair, connects the rods 3, 8, and 7, constituting an arm of the chair.

The several rods above referred to are of 75 ordinary metal pipe connected by couplings 11, certain of these couplings being T-couplings, and other angles as is necessary in accordance with the location. This hollow rod or pipe construction insures a strong and rigid chair, and in addition provides two 80 parallel tubular guides at the right hand side and front of the chair for two adjustable posts 12 and 13. These posts 12 and 13 fit snugly within tubular rods 8 and 7, and are adjustable vertically in the tubular 85 rods as will be hereinafter explained. The posts 12 and 13 at their upper ends are connected by T-couplings 14, with horizontal rods 15. The rods and the T-couplings have rigid connection. The rods 15 support a 90 desk 16, which latter is provided on its lower face with channel guides 17 receiving the ends of rods 15 and adapted to slide on the rods to adjust the desk horizontally toward and away from the back of the chair. 95

A toggle lever 18 connects the two rods 15. This toggle lever, at one end, is pivotally connected by sleeves 19 with the rods 15, and these sleeves are secured against movement longitudinally of the rods. The 100 other end of the toggle lever is connected by sliding sleeves 20 with the rods 15, so that while the toggle levers permit the rods to move relative to each other and vary the distance between the rods, such toggle lever 105 prevents any possibility of the rods moving out of parallelism.

As above stated, the posts 12 and 13, which support rods 15, are located within the tubular rods 8 and 7, and are secured at vertical 110

adjustments in said tubular rods by means of depending links 21 and clamps 22. The clamps 22 are positioned around the tubular rods 8 and 7, and are connected by bolts 23 and wing nuts 24, so that by the adjustment of the nuts, the clamps may be either secured or released, and when released, will permit the clamps to slide on the vertical rods.

The upper ends of the links 21 are connected by sleeves 25 with the rods 15, and while the construction of links and clamp are precisely alike for the front and rear rod 15, the links 21 of the rear rod 15 are shorter than the links of the forward rod 15, as the rear rod 15 is adjusted only to vary the height of the desk, while the front rod 15 is adjusted to vary the angle as well, and requires a greater length of adjustment.

Under the seat 1, I locate a sliding drawer 26 having a handle 27 thereon to move the same. The drawer 26 is supported on the tubular framework above described, and in addition is supported by a transverse rod 28, and has a clip 29 mounted to slide on the rod 28, said clip limiting the outward movement of the drawer to prevent it from being entirely withdrawn.

While I have illustrated the desk in a horizontal position, it is to be understood that it may be inclined as desired by raising and lowering the front clamp 22, and the height of the desk may be varied by raising and lowering both clamps 22.

The position of the desk relative to the occupant of the chair may be varied by sliding the desk on the rods 15, and hence each desk can be positioned precisely as desired.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

50 1. The combination with a chair having vertically adjustable posts at one side, horizontal rods supported by the posts, a desk mounted to slide on the rods, and a toggle lever connecting the rods, substantially as described.

60 2. The combination with a chair having vertically adjustable posts at one side, horizontal rods supported by the posts, a desk mounted to slide on the rods, a toggle lever connecting the rods, and said toggle lever having fixed pivotal connection with each rod and having sliding pivotal connection with each rod, substantially as described.

65 3. The combination with a chair having vertically adjustable posts at one side, hori-

zontal rods supported by the posts, a desk mounted to slide on the rods, a toggle lever connecting the rods, each rod having two sleeves thereon, one of each pair being mounted to slide on the rod, and said toggle lever pivotally connected to the four sleeves, substantially as described.

4. The combination with a chair having vertical tubular guides, posts telescoping in the guides, horizontal rods supported by the posts, a desk mounted to slide on the rods, devices connected to the rods and adjustably secured to the tubular guides, and a toggle lever connecting the rods, said toggle lever at one end movably connected to the rods, substantially as described.

5. The combination with a chair having vertical tubular guides, posts telescoping in the guides, horizontal rods supported by the posts, a desk mounted to slide on the rods, clamps adjustable on the tubular guides, links connecting the clamps with the rods, and a toggle lever connecting the rods, said toggle lever at one end movably connected to the rods, substantially as described.

6. The combination with a chair having parallel vertical tubular guides at one side of the chair, of posts telescoping in the guides, horizontal rods secured to the upper ends of the posts, a desk having guides on its under face receiving the ends of the rods and slidably mounted thereon, a toggle lever connecting the rods, and means for securing the posts at various adjustments in the tubular guides, substantially as described.

7. The combination with a chair having parallel vertical tubular guides at one side of the chair, of posts telescoping in the guides, horizontal rods secured to the upper ends of the posts, a desk having guides on its under face receiving the ends of the rods and slidably mounted thereon, a toggle lever connecting the rods, clamps slidably mounted on the tubular guides, and links connecting the clamps with the rods, substantially as described.

8. The combination with a chair having vertical tubular guides, of posts telescoping in the guides, horizontal rods secured to the upper ends of the posts, a desk having guides on its under face receiving the ends of the rods and slidably mounted thereon, means for securing the posts at various adjustments in the tubular guides, four sleeves mounted on the rods, two of said sleeves fixed to the rods and the other two sleeves mounted to slide thereon, and a toggle lever connecting the four sleeves, substantially as described.

9. The combination with a chair having vertical tubular guides, of posts telescoping in the guides, horizontal rods secured to the upper ends of the posts, a desk having guides on its under face receiving the ends

of the rods and slidably mounted thereon, clamps slidably mounted on the tubular guides, links connecting the clamps with the rods, four sleeves mounted on the rods, 5 two of said sleeves fixed to the rods, and the other two sleeves mounted to slide thereon, and a toggle lever connecting the four sleeves, substantially as described.

In testimony whereof I have signed my name to this specification in the presence of 10 two subscribing witnesses.
